UNITED STATES PATENT OFFICE.

ALEXANDER H. HANDLAN, OF ST. LOUIS, MISSOURI.

HAND LANTERN.

Application filed October 24, 1925. Serial No. 64,508.

This invention relates generally to hand lanterns, and particularly to a hand lantern of the type used by trainmen for transmitting signals and which is provided with a movable globe holder, or windbreak, adapted to hold the lantern globe in position and force said lantern globe into firm contact with its seat.

As is well known, hand lanterns of the type disclosed herein include each a guard frame, a globe seat at the lower portion of said guard frame and a globe holder, or windbreak as it is usually called, at the upper portion of said guard frame. In giving 10 certain signals it is imperative that the air enter the lantern only at points of ingress definitely determined in order that the flame may be sustained, and if during the giving of these signals a current of air be permitted 15 to enter the lantern between the globe and its seat the flame will be dimmed, or probably completely extinguished. In an attempt to compel firm contact between the bottom face of the globe and the globe seat so that air may not enter at this point, manufacturers of hand lanterns have been providing the lanterns with the globe holders mentioned above, and have in this manner obtained reasonably firm contact between the 20 bottom face of the globe and the globe seat.

Formerly the globe holder, or windbreak, of a lantern was not usually removed from the lantern during the life of said lantern, due to the fact that the globe holders, or windbreaks, were capable of lasting as long as the lanterns, and because of this fact, together with the fact that the user of a lantern used only a single type of globe with his lantern, there was no great necessity for 25 the removal of said globe holders, or windbreaks. At the present time, however, there are several types of lantern globes on the market and the globes of the different types are of different heights, so that if a lantern 30 be provided with a globe holder adapted for use with a globe of one type, a globe of another type may not be used with said globe holder. In view of the foregoing, I have devised the lantern disclosed in the present application, which is so constructed that by a 35 very simple operation the globe holder associated with the lantern may be removed and another globe holder substituted for the first mentioned globe holder. Because of this arrangement globes of any of the types now in

use may be used with the same lantern, it merely being necessary to remove the globe holder associated with the lantern and replace it with a different globe holder when it is desired to change from the use of one type 60 of globe to the other.

Another object of my invention is to provide a lantern having my improved removable globe holder associated therewith with improved means for controlling the passage 65 of air through the lantern body.

With the foregoing and other objects in view, the invention comprises the novel construction, combination and arrangement of parts hereinafter more specifically described 70 and illustrated in the accompanying drawings, wherein is shown the preferred embodiment of the invention. However, it is to be understood that the invention comprehends changes, variations and modifications 75 which come within the scope of the claims hereunto appended.

Fig. I is a view partly in side elevation and partly in vertical section, showing a lantern constructed in accordance with my invention, said lantern being provided with a lantern globe of a type now in general use. 80

Fig. II is a fragmentary vertical section of my improved lantern showing a comparatively short lantern globe associated therewith. 85

Fig. III is a cross section on line III—III of Fig. I.

In the drawing A designates a hand lantern of the type used by trainmen, which lantern is provided with an oil font holder B secured in any suitable manner, as for instance by welding, to a guard frame C, and said oil font holder is provided with air induction ports D. E designates a globe seat which is arranged within the oil font holder B and is adapted to receive the bottom face of the lantern globe F. The globe seat E is a continuation of an annular wall G which is spaced apart inwardly from the side wall of the oil font holder to provide an annular air space H. Located at the upper end of the annular wall G is a row of perforations J through which air may pass 90 from the air space H into the interior of the lantern globe F. The outer edge of the globe seat E is spaced apart from the inner face of the side wall of the oil font holder B to provide an annular space K, and the upper edge of said side wall of said oil 95

100

2
font holder is spaced apart from the outer face of the adjacent portion of the globe F to provide an annular space L.

In view of the arrangement just described, it is apparent that air may pass through the air induction ports D into the annular space H, and that some of said air will pass through the perforations J into the interior of the globe to sustain the flame therein. If, however, an excessive amount of air passes into the space H, all of said air will not pass through the apertures J into the interior of the globe to disturb the flame therein, but a portion of said excessive amount of air will pass through the spaces K and L to the outer atmosphere. Also if an excessive amount of air passes through the space K into the space H only a portion of said air will pass through the apertures J, the excess passing from the space H through the ports D.

M designates the dome of the lantern, which is usually pivotally connected to the guard frame C, and said dome is ordinarily provided with a suitable latching device so that it may be fastened in a closed position, but as said latching device and the arrangement of hinging the dome to the guard frame are common, they have not been shown in the drawing and will not be described herein.

N designates my improved globe holder, or windbreak, which includes an annular plate 1 arranged transversely of the lantern. Located at the inner edge of the annular plate 1 is an upwardly extending annular wall 2 at the upper end of which an annular inwardly extended wall 3 is arranged. 4 designates an annular vertical wall which is arranged at the inner edge of the inwardly extended wall 3. The plate 1 and the walls 2, 3 and 4 are preferably, though not necessarily, formed integral with each other. By referring to Fig. I it will be noted that the walls 2 and 3 of the globe holder provide an annular seat for the upper portion of said globe F. 5 designates a coil spring, preferably conical in shape, which is interposed between the top wall of the dome M and the top face of the annular wall 3 of the globe holder N. The coil spring 5 is adapted to exert downward pressure, thus causing the globe holder to be forced into firm contact with the top face of the globe F, and as a consequence the bottom face of said globe will be forced into firm contact with the globe seat E, whereby the passage of air between the bottom face of the globe and the globe seat is prevented.

60 Secured by welding or otherwise to the inner face of the breast portion M' of the dome M as an annular flange 6 provided with screw threads, and 7 designates a cup-shaped member having an annular side wall 7^a provided with screw threads, and a horizontal

bottom wall 7^b which overlaps the outer edge portion of the annular plate 1, said bottom wall 7^b being provided with a central opening 8 of considerably greater diameter than the adjacent portion of the globe F, through which opening the lantern globe extends. The diameter of the cup-shaped member 7 is such that the screw threads on the annular side wall thereof will engage the screw threads on the annular flange 6, thus permitting said cup-shaped member to be screwed on said annular flange, as shown most clearly in Fig. I. It will be apparent that when the cup-shaped member 7 is screwed on the annular flange 6 as described and shown in the drawing, the bottom wall 7^b of said cup-shaped member will act as a stop to limit the downward movement of the globe holder N, the plate 1 of said globe holder being adapted to contact with the bottom wall of said cup-shaped member.

By referring to Fig. I of the drawing it will be noted that the annular side wall of the dome M is provided with a row of perforations 9 adjacent to the lower end of said annular side wall and a pair of rows of perforations 10 adjacent to the upper end of said wall. Because of the arrangement of the perforations 9 and 10 the vertical annular wall of the dome is provided with an imperforate portion between the row of perforations at the lower end of the wall and the pair of rows of perforations at the upper end of said wall. The presence of this imperforate portion is of the utmost importance in that it provides a chamber in which a body of air in a relatively quiet state is maintained, which body of air tends to cause a breaking-up, diffusion and checking of the undesirable air currents within the dome, thus preventing disturbance of the flame. Arranged within the dome M and secured to a wall thereof is an annular inclined baffle 11 which is intended to deflect upwardly any air which enters the dome through the perforations 10.

When the dome of a lantern constructed in accordance with my invention, as shown in Fig. I, is being moved to a closed position, the globe holder N will contact with the top face of the lantern globe, said globe holder being moved upwardly to separate the plate 1 from the bottom wall of the cup-shaped member 7. With the parts positioned as described, the coil spring 5 will force the globe holder N into firm contact with the top portion of the lantern globe, and the bottom face of said lantern globe will in turn be forced into firm contact with the globe seat to prevent the passage of air at that point. Some of the air necessary to support combustion within the globe F will enter said globe through the ports D, space H and ports J, as already explained. Other air will pass through the opening 8 in the bot-

tom wall of the cup-shaped member 7 into the interior of said cup-shaped member, said air then passing horizontally between the bottom wall of said cup-shaped member 5 and the plate 1 of the globe holder N. Said air will then pass upwardly around the outer edge of the plate 1 into the dome M, with the result that there is always a sufficient amount of fresh air adjacent to the globe 10 holder to maintain the flame when a downward movement of vapor within the globe is caused. Also, because of the tortuous path traveled by the air, no swiftly moving currents are produced within the dome 15 which would tend to disturb the flame.

Thus far I have described a lantern as it will be arranged when a globe of the type shown in Fig. I is used. Assume now that a lantern provided with the globe holder and globe shown in Fig. I were in use, and the user desired to replace the globe with a globe of the short type illustrated in Fig. II. In this event the cup-shaped member 7 would be unscrewed from the flange 6 and the globe 20 holder N would be removed from the lantern. The globe-holding means employed when a globe of the short type is used comprises, in addition to the globe holder N', which is an exact counterpart of the globe 25 holder N already described, a downwardly extended outwardly flared annular member 12, said member 12 being secured at its upper end in any suitable manner to the globe holder N'. The annular member 12 is of 30 such length and its diameter is such at its lower end that it will engage the top portion of the short lantern globe, as shown in Fig. II. Associated with the globe holder N' and annular member 12 is a cup-shaped 35 member 7' exactly like the cup-shaped member 7 illustrated in Fig. I, the bottom wall of the cup-shaped member 7' being arranged between the plate 1 of the globe holder N' and the outwardly flared wall of the annular 40 member 12, whereby said cup-shaped member is caused to be a part of a unit composed of the globe holder N', annular member 12 and said cup-shaped member. To attach the globe-holding means illustrated in Fig. II to 45 a lantern so that the short type of globe may be used, the lower end of the coil spring 5' is caused to contact with the horizontal wall 3' of the globe holder N' and the cup-shaped member 7' is then screwed on the 50 screw-threaded annular flange 6', so that the combined globe-holding mechanism is connected to the dome of the lantern, as 55 shown in Fig. II.

It is apparent from the foregoing that it 60 is a very simple matter to change the globe-holding mechanism so that one or the other type of globe mentioned herein may be employed, and therefore the necessity that the

user be limited to the use of one type of globe is eliminated. It is also apparent that 65 other globe holders may be provided which may be used with globes of types other than those mentioned.

When a lantern globe of the short or any other type is used in connection with my improved lantern the air is controlled as already described in connection with the use of a lantern having a globe of the type shown in Fig. I.

I claim:

1. A lantern having a dome, a globe, a seat for the bottom face of said globe, a spring-pressed globe holder within said dome, and means whereby said globe holder is retained in position with relation to said dome, the last mentioned means including a cup-shaped member having attaching means whereby said member may be secured in place and a portion which overlaps a portion of said globe holder and limits the downward movement of said globe holder, said member being removable whereby said globe holder may be removed from the lantern.

2. A lantern having a dome, a globe, a seat for the bottom face of said globe, a spring-pressed globe holder within said dome having an annular plate arranged transversely of the lantern, an annular flange secured to a portion of said dome, and a member whereby said globe holder may be retained in place relative to said dome, said member having a portion provided with means whereby said member may be removably attached to said annular flange and a portion which overlaps said annular plate of said globe holder, the last mentioned portion being adapted to limit the downward movement of said globe holder and said member being removable to permit removal of said globe holder.

3. A lantern having a dome, a globe, a seat for the bottom face of said globe, a spring-pressed globe holder within said dome having an annular plate arranged transversely of the lantern, an annular flange secured to a portion of said dome and provided with screw threads, and a member whereby said globe holder may be retained in place relative to said dome, said member having a portion provided with screw threads adapted to engage the screw threads on said annular flange and a portion which overlaps said annular plate of said globe holder, the last mentioned portion of said member being adapted to limit the downward movement of said globe holder and said member being removable to permit removal of said globe holder.

In testimony that I claim the foregoing I hereunto affix my signature.

ALEXANDER H. HANDLAN.
